UNITED STATES PATENT OFFICE.

ABBOT A. LOW, OF HORSESHOE, AND HARRY HERTZBERG, OF NEW YORK, N. Y.; SAID HERTZBERG ASSIGNOR TO SAID LOW.

VAPORIZING DEVICE FOR EXPLOSIVE-ENGINES.

1,035,614.

Specification of Letters Patent. Patented Aug. 13, 1912.

Application filed May 16, 1908. Serial No. 433,238.

To all whom it may concern:

Be it known that we, ABBOT A. Low and HARRY HERTZBERG, citizens of the United States, and residents, respectively, of Horseshoe, county of St. Lawrence, and State of New York, and of the city of New York, borough of Brooklyn, county of Kings, and State of New York, have invented certain new and useful Improvements in Vaporizing Devices for Explosive-Engines, of which the following is a specification.

This invention relates to explosive engines and has for its object the provision of a simple and efficient device for vaporizing the fluid to form the explosive charge.

The device shown in the accompanying drawings and which will be described hereinafter is particularly adapted for engines of the type using kerosene oil. In engines of this type a common means of vaporizing the oil has been to cause the same to be delivered in a stream or spray against a hot plate in the cylinder head, thus causing the same to vaporize and mix with the proper amount of air to form the explosive mixture.

My invention comprises a device, substantially in the form of a wire mesh or screen, which is heated by suitable means and through which the liquid oil is caused to pass. By reason of the peculiar construction a relatively large surface is provided against which the liquid oil will contact in passing through the screen and is more quickly and thoroughly vaporized, thus producing more satisfactory and efficient results.

In the drawings accompanying this specification is shown a simple embodiment of my invention as adapted to be used in connection with a kerosene engine.

In the several views of the drawings like parts have been given the same reference numerals.

Figure 1 is a side elevation of a portion of an engine such as described. Fig. 2 is an enlarged sectional elevation of a portion of said engine. Fig. 3 is a detail view of the vaporizing device. Fig. 4 is a perspective view showing a modification of the vaporizing device.

A portion of an engine cylinder is shown at 1. At the upper end of this cylinder is a valve-chamber 2 in which is positioned the usual admission valve controlling the admis-

sion of the explosive mixture to the engine cylinder 1 operated by the lever 3. A mixing chamber 4 communicates with the engine cylinder through the valve chamber 2. This mixing chamber is shown in Fig. 2 in section.

The vaporizing device as shown in Fig. 3 in detail is also shown in section positioned in the mixing chamber in Fig. 2. This device consists of a frame, preferably of insulating material, such as shown at 5. Mounted in this frame are a series of conductors, such as 6, running from side to side of said frame in parallel lines and provided with suitable wire connections 7 through which connection is made to a source of current. These conductors are of such size and material that the current passing therethrough will heat the same to the required amount and in which the amount of heating may be regulated by the amount of current passing therethrough. Several frames or sets of conductors may be superimposed upon each other, as shown in Fig. 2. The conductors or wires in each frame are so arranged that the wires of adjacent frames run transversely to each other while the wires of alternate frames run intermediary of each other. When placed together the wires of the several frames are connected together in series with one another and provide a mesh or screen which may be electrically heated from a suitable source of current. The appearance of this screen when formed as above described by superimposing several sets of conductors one upon another is shown in Fig. 3. It will be noted that this construction provides a relatively large contact surface for any fluid passing through the screen.

A modification of the frame for the wire mesh is shown in Fig. 4. In this construction a single frame 5' takes the place of the several individual frames 5 in the construction just described. The several sets of wires are mounted in this frame 5' so as to be relatively positioned as described for the superimposed frames shown in Fig. 2 and also in Fig. 3.

The operation of the engine is as follows: The oil is forced through the mixing chamber from the supply pipe 8 and striking against the wires 6 of the screen which are heated electrically, is vaporized. This operation occurs during the upward stroke of

- 2
- the piston and the vaporized oil is carried through the screen to the left as shown in Fig. 2. Upon the return stroke of the piston the oil vapor is again drawn through the screen and mixes with the air which is at the same time drawn in from the supply pipe 9. This forms the explosive mixture which is then drawn into the cylinder 1 through the admission valve.
- 10 It will be seen that by means of this construction the entering stream of oil is broken up and scattered by the wire mesh and is quickly vaporized by reason of the large heating surface presented by the screen.
- 15 This not only results in a quicker vaporization of the oil but the action is much more thorough and produces a much more efficient explosive mixture.
- The advantages obtained by the simple and compact construction by means of which the necessity of heating the vaporizer artificially by outside means, such as a gaso-
lene torch, etc., are avoided, will be obvious.
- 20 As many changes could be made in the above construction and many apparently widely different embodiments of my invention designed without departing from the scope thereof, we intend that all matter contained in the above description or shown in the accompanying drawings shall be interpreted as illustrative merely of an operative embodiment of our invention and not in a limiting sense.
- 25 What we claim is:
- 30 1. In combination with an explosive engine, a mixing chamber provided with fluid admission means and an outlet to the en-
gine cylinder located adjacent one end thereof and an air inlet intermediary of the ends thereof, and a vaporizer comprising a screen positioned in the mixing chamber intermediary of the air inlet and the end of the chamber opposite the fluid admission and the outlet to the engine cylinder, whereby the fluid is first forced through the screen and partially vaporized and then repassed through the screen in the opposite direction, then mixed with the air and drawn into the engine cylinder, and means for heating said screen.
- 35 2. In combination with an explosive engine, a mixing chamber provided with fluid admission means and an outlet to the engine cylinder located adjacent one end thereof and an air inlet intermediary of the ends thereof, and a vaporizer comprising a screen positioned in the mixing chamber and dividing the chamber into two parts, one part having the air inlet and outlet to the engine cylinder opening therein and the other part closed by said screen, whereby the fluid is first forced through the screen and partially vaporized and then repassed through the screen in the opposite direction, then mixed with the air and drawn into the engine cylinder, and means for heating said screen.
- Signed at Brooklyn, in the county of Kings and State of New York, this 12th day of May, 1908.
- ABBOT A. LOW.
HARRY HERTZBERG.
